UNITED STATES PATENT OFFICE

ABRAHAM NOVICK, OF FLUSHING, NEW YORK, ASSIGNOR TO F. L. SMITH MACHINE CO., INC., OF NEW YORK, N. Y., A CORPORATION OF NEW YORK

SHEET-FOLDING MECHANISM

Application filed January 29, 1926. Serial No. 84,579.

This invention relates to mechanism for folding paper or like sheet material for the purpose of forming articles, such as envelopes, and is in the nature of an improvement 5 upon the machine disclosed in my prior Patent No. 1,551,903 for sheet folding mechanism, granted September 1, 1925.

The said prior patent is concerned with a folding mechanism in which the folding 10 members have a double motion; that is, in which they are movable, first transversely of the blank, and then in the plane of the blank. It is more particularly concerned with the provision of high speed operating means for 15 folding members of this kind, and employs for this purpose separate operating means for imparting the two movements to the folding members, the means for imparting the movement in the plane of the blank, which 20 is a long, fast movement, being much lighter and having less inertia than the means for imparting the movement transversely of the blank, this being a short, relatively slow movement.

25 In the particular embodiment of the invention illustrated in said prior patent the envelope blank is fed into position to be folded, and is there arrested and adjusted preparatory to the folding operation.

30 The principal object of the present invention is to provide a machine wherein the blanks may be folded while in motion, without being arrested in their progress through the machine, the purpose being to expedite the 35 operation of the machine and thereby increase its output.

Other objects and advantages will hereinafter appear.

In the drawings:

40 Figure 1 is an elevation of a portion of an envelope making machine having the invention embodied therein;

45 Figure 2 is a fragmentary, sectional, side elevation of a portion of said machine substantially on the line 2-2 of Figure 1;

50 Figure 3 is a plan view of the envelope blank with its side flaps folded, the hold-down rolls being indicated in the relation which they bear to the blank in this stage 55 of the operation;

Figure 4 is a plan view of certain parts of the side flap folding mechanism;

Figure 5 is a sectional elevation of said mechanism substantially on the line 5-5 of Figure 1; and

Figures 6 to 10 are diagrammatic views illustrating the manner in which the side flaps of an envelope are folded by the folding mechanism.

The machine, which is generally similar to the machine of my prior patent referred to above, comprises a frame, portions of which are represented by the parts 8 and 9. Between these frame members, and inclined to the vertical, are forming blades 12 and 13 which cooperate with the blank to be folded. The means by which the blanks are fed downwardly behind the forming blades 12 and 13 comprises a feed belt 15 the lower reach of which is supported by a pulley 16 (Figure 70 2), the front surface of this belt being in substantially the same plane as the back surfaces of the forming blades 12 and 13 and as the front surfaces of certain fixed guides 18 and 19 (Figures 6 to 10). Frictional engagement between the envelope blanks and the belt 15 is increased by rollers yieldingly pressed toward the belt. It will be understood that the mechanism herein illustrated forms only part of the complete machine, and that the machine includes means for delivering blanks to the belt 15 in definitely timed relation. The mechanism whereby this timed feeding is secured is desirably like that disclosed in my pending application, Serial No. 637,626, for sheet feeding mechanism, filed May 9, 1923. Such feeding means and the folding mechanism to be described herein are driven through suitable gearing

80 from a common line shaft or other suitable common source of power (not shown), the operation of the folding means being thus definitely synchronized with the arrival of the blanks in position to be folded. In Figure 6 an envelope blank is shown in a position to which it has been carried by the belt 15, and in which it is ready for the side flaps to be folded over the forming blades 12 and 13 by the folding mechanism which will be hereinafter described,

Each of the said forming blades is supported on a block 27, each of which blocks is adjustably supported on a cross frame member 30 upon which it is secured in place by set screws 38. Owing to the fact that the locations of the blocks 27 may be adjusted laterally of the machine upon the cross frame member 30 when the set screws 38 are loosened, it will be understood that the position 5 of the forming blades 12 and 13 with reference to the belt 15 may be easily adjusted for different sizes of envelope blanks to be folded.

In the machine as illustrated in my prior patent the forming blades were reciprocated 15 longitudinally to cooperate with a bottom flap folder and to advance the blanks beyond the side folding station. In the present machine, however, the bottom folder is omitted from this part of the mechanism and the 20 forming blades remain stationary.

Before proceeding with the description of the details of the side flap folding mechanism, it will be helpful to describe the function of this mechanism with the aid of Figures 6 to 10. These figures all show, in a more or less diagrammatic manner and in cross section, an envelope blank A located between the forming blades 12 and 13 and the fixed guides 18 and 19, and in engagement with the 25 conveyor belt 15. Devices 90 which will be called "flap lifters" and will be hereinafter described, are diagrammatically represented; and the folding elements themselves are diagrammatically shown as comprising elements 91, and elements 92 which cooperate with the forming blades 12 and 13 to effect the folding of the side flaps of the envelopes. Above the plane of the envelope blank, and slightly to the left of the belt 15 is a finger 93, 30 the form of which is shown in Figure 2, which serves to retard the folding over of one of the side flaps of the envelope, so as to insure that this flap will lie on top of the other flap which is gummed at its edge as indicated at 94. Figure 6 shows the envelope blank in the act of passing downwardly into the position shown in Figure 1 in which it is ready to be folded. At this time, the side flap lifters 90 are holding the side flaps of the envelope slightly raised so that they will not come into engagement with the creasing and folding elements 91 and 92. Figure 7 shows the elements 91 and 92 raised and beginning to perform the folding operation, the side flap lifters being at this time retracted. Figure 8 shows the elements 91 performing their function of folding the flaps of the envelope blank over the edges of the forming blades 12 and 13; and shows the elements 92 mid-way 35 of their folding movements. It will be noted that at this time the left flap of the envelope is engaging and is being delayed in its movement by the finger 93. Figure 9 shows the folding elements at their extreme folding 40 positions. The side flap folding operation

has now been completed. As soon as the envelope flaps have been folded to the positions shown in Figure 9 the folding elements 91 and 92 are withdrawn, from the position shown in Figure 9 and thru the positions 45 shown in Figures 8 and 7, to the position shown in Figure 6, ready for operation on another envelope blank. Figure 10 shows the machine parts and the blank in the positions corresponding to Figure 3, this being intermediate between the positions of Figures 8 and 9.

It is of very great importance that this folding mechanism be capable of high speed 50 operation since this mechanism is required to act on the blanks while they are in motion. It is obvious that slow acting side folders would necessitate a slowing down of the blank feeding, and that this would result in a diminution of the output of the machine.

In the particular embodiment of the invention shown in the drawings, the side flap folding mechanism is actuated from a constantly driven shaft 80. The folding elements 91 are moved in two directions, one of these directions being substantially perpendicular to the plane of the envelope blank, and the other direction being substantially parallel with said plane. The manner in which the elements 91 are supported and moved will be first described. Referring to Figure 4, it will be seen that each element 91 is carried by a lug 97 which is secured by a bolt 98 to a lug 99 which is integral with a plate 100 adjustably secured to a slide member 101 by means of a bolt 102 extending thru a slot in said member. The member 101 is supported so as to be capable of small transverse movement and more extensive longitudinal movement in a supporting frame 105 provided with a base plate 106 which is bolted to the frame 8 or 9 of the machine by bolts 108. As best shown in Figure 5, the frame 105 is provided with a recess 109 in which the member 101 is located; the plates 110 and 111 being provided for retaining the member 101 within the slot 109 without interfering with its movement therein. Transverse movement of the slide member 101 in the slot 109 is effected by a plate 114 arranged 105 for longitudinal sliding movement in a channel provided in the frame 105 and extending at right angles to the slot 109. The form 110 of the plate 114 will be apparent from Figures 4 and 5. Said plate 114 is retained within the channel in the frame 105 by means of plates 116 which are secured to the frame 105 by screws 117 or in any other suitable manner. At its end nearest the slide member 101, the plate 114 is preferably enlarged and 115 provided with a downwardly extending plate 119 which extends into a slot 120 in the slide member 101. It will be understood that longitudinal movement of the plate 114 will 120 serve to move the member 101 transversely 125 130

in the slot 109, without interfering with the longitudinal movement of said member 100. Near its other end, the plate 114 is provided with a slot 121 in which, on a pin extending across said slot, is mounted a roller 122. This roller 122 is engaged by the forked ends 124 of a lever 125 (Figure 2) pivotally mounted on a shaft 127 which is rotatably mounted in the frames 8 and 9 of the machine. At its lower end, lever 125 is provided with a cam follower 128 adapted to cooperate with a cam 130 secured to the shaft 80. The lever 125 is biased to a position in which the cam follower 128 constantly makes contact with the surface of the cam 130, by a spring 132 which is secured at one end to the frame of the machine and at the other end to an arm 133 extending outwardly from the lever 125. It will be obvious that as the cam 130 rotates, the lever 125 is rocked, thereby causing reciprocation of the slide 114 in the supporting frame 105; and that this movement causes transverse movement of the slide member 100 in the slot 109. The means by which each slide member 100 carrying the element 91 is reciprocated longitudinally, is best shown in Figures 1 and 4. As therein shown, each slide member 100 is actuated by a cam 135 mounted on and secured to the shaft 80. Cooperating with the cam 135 is a cam follower 137 mounted in the end of a lever 138 pivotally supported on a bracket 140 attached to the frame of the machine. Attached to the upper end of the lever 138 by any suitable form of universal joint, is a connecting rod 142 which at its other end is connected thru a universal joint 144 with the slide member 100. The lever 138 is biased to the position in which the cam follower 137 engages the cam 135, by means of the spring 146 attached at one end to a bracket 147 extending from the frame of the machine, and at the other end to an arm 148 extending from the lever 138. It will be apparent that the connections between the lever 138 and the slide member 100 are such that the transverse movement of the member 100, in the manner hereinbefore described, will not interfere with the longitudinal movement of the member 100 by the cam 135. Furthermore, it will be noted that the transverse and longitudinal movements of the slide member 100 are caused by separate cam mechanisms which can be independently adjusted, thereby facilitating proper setting and control of the folding mechanism.

The side flap folding elements 92 have a greater longitudinal movement than the folding elements 91. As best shown in Figures 4 and 5, each folding element 92 is pivotally attached at its rear end to the forked end 150 of a lever 151 which is pivotally attached at its other end to a screw 153 extending from the bottom of the plate 114 and thru a slot 65 in the frame member 105. Pivotally secured to the lever 151 by means of a pin 155 (Figure 5), is a link 156 which at its other end is pivotally attached to the slide member 100, as shown in Figure 4. A spring 159, attached at one end to the folding element 92 and at the other end to a lug on the link 156, serves to hold the folding element 92 yieldingly with its folding end in engagement with the other folding element 91. With the construction just described, it will be apparent that, as each slide member 100 is reciprocated longitudinally, the movement of its folding element 91 will be comparatively short, while the longitudinal movement of its folding element 92 will be much greater, the comparative extent of these movements being shown in Figures 6 to 9. This comparatively great movement of the folding elements 92 is facilitated by the lightness and consequent lack of inertia of these elements and of the parts by which they are actuated. It will of course be understood, however, that when certain sizes of envelopes are to be folded the elements 92 may be dispensed with as unnecessary, and the entire folding operation may be performed by the elements 91.

It is to be noted that in the transverse movement of the member 100, which is a short slow movement, all of the parts attached thereto move; whereas in the longitudinal movement of said member, which is a long fast movement, only some of the attached parts move. In view of this fact, the weight and consequently the inertia of the parts moving longitudinally are less than the weight and inertia of the parts moving transversely. This construction of having the fast moving parts of less weight than the slow moving ones, is a very important factor in high-speed operation of a machine of this class.

It will be seen that this organization is especially well designed to operate upon the blanks while they are in motion, its action being so rapid that the blanks may be fed past it continuously at a high rate of speed.

The means by which the side flap lifters 90 are supported and actuated will now be described. As shown in Figures 1 and 2 each side flap lifter 90, which is in the form of a wire with a hooked end, is adjustably mounted in a block 165 carried by the end of a link 166 which is adjustably secured at its other end by a bolt and wing nut 167 to an arm 169 attached to the end of a rod 170. The rod 170 is slidingly supported in a bearing 172 extending from a yoke 173 mounted on a bar 175 supported in the frame members 8 and 9, and upon a shaft 177 journaled in said frame members 8 and 9. The yoke 173 may be secured at any desired location transversely of the machine by set screw 179. The rod 170, near the end which is remote from the side flap lifter, is provided with a slot across which extends a pin 181. The pin 181 is en-

gaged by the forked ends of a lever 182 which is secured in any suitable manner, as by a set screw 183, to the shaft 177. The shaft 177 is rotatably reciprocated, in order to rock the levers 182 and cause reciprocation of the rods 170 carrying the side flap lifters 90, by means of a cam 184 secured to the shaft 80. Cooperating with the cam 184 is a cam follower 185 which is mounted on a lever 187 mounted on the shaft 127 and secured thereto by a set screw 188; and a link 189 pivotally connects the lever 187 with an arm 190 secured to the shaft 177. With this arrangement, it will be obvious that as the cam 184 rotates, it will cause the side flap lifters 90 to reciprocate from the position shown in Figure 6, in which said lifters are keeping the envelope blank from engaging with the side flap folding elements 91 and 92, to the position shown in Figures 7, 8 and 9 in which the side flap lifters are out of the way of the lower edge of a descending envelope blank.

It will, of course, be understood that the various cams 130, 135 and 184, which are secured to the shaft 80, are so designed and angularly located with reference to one another that the various mechanisms actuated by them will properly cooperate with one another and with the other elements of the machine, to the end that the envelope blanks may properly pass thru the machine and be operated upon.

To this end the shaft 80 may be connected to drive the blank feeding belt 15 through a train of gearing comprising gears 80^a and 16^a fast, respectively, on shafts 80 and 16^b.

The manner in which the finger 93, the function of which is illustrated in Figure 8 and has been hereinbefore described, may be supported, is illustrated in Figure 2. In this figure, the finger 93 is shown as frictionally held in a hole in the split end of a block 193 which may be contracted by means of a bolt 194. The block 193 is pivotally mounted on a pin 195 extending from a bracket 196 secured to a portion 197 of the frame of the machine. The upper end of the block 193 is shown slotted and capable of being drawn together by a bolt 198, for the purpose of frictionally holding the block 193 in any desired position on the pin 195. Of course, the finger 93 may be supported in any other suitable manner which will provide for its proper adjustment.

To summarize briefly, the blanks enter the side folding part of the machine between the belt 15 and a cooperating belt 199. They pass thence beneath the forming blades 12 and 13, being pressed against the belt 15, first by roller 200 and then by the rollers 19^a. As they come within the range of the side folders, the side folders move upward and inward, folding the blanks in the manner illustrated in Figures 6 to 10, as already described. As the blanks pass beyond the low-

ermost roll 19^a, their inturned flaps pass beneath a feed roll 201 which serves both to adhesively connect the flaps and to cooperate with belt 15 in feeding the blanks. This feed roll, in conjunction with the belt 15, delivers the blanks between cooperating belts 202 and 203, running on pulleys 204 and 205. These belts continue the progress of the blanks to other mechanism, such as the bottom flap folding mechanism which, in the present embodiment, is a separate part of the organization from the side folding mechanism described.

Variations may be resorted to within the scope of the invention, and parts of the improvements may be used without others.

What I claim is:

1. In an envelope making machine, in combination, side flap folding means, means for imparting short, relatively slow movements transversely of the blanks, and long fast movements in the plane of the blanks, means for feeding the blanks uninterruptedly past said folding means, the folding means being constructed and arranged to operate on the blanks while they are in motion, and the fast moving means being lighter than the relatively slow moving means.

2. In an envelope folding mechanism, the combination with means feeding the blanks uninterruptedly, of means movable transversely of the blanks and in the plane thereof for forming longitudinal folds in the blanks while they are in motion.

3. In an envelope folding mechanism, in combination, stationary forming blades, means for feeding the blanks continuously past the forming blades, and side folding means operable to fold the side flaps of the blanks while the blanks are in motion, said side folding means being arranged for successive movements transversely of and parallel to the blank plane.

4. In an envelope folding mechanism, in combination, means for feeding blanks uninterruptedly, and side flap folding means operable on the blanks while in motion, comprising folders, and means for imparting long, fast movements to the folders substantially parallel to the blank plane, and relatively short, slow movements to the folders transversely of said plane.

5. In an envelope folding mechanism, in combination, means feeding the envelope blanks, means movable transversely of and substantially parallel to the blank plane for folding the envelope blanks during the feeding thereof, and means driving the feeding means and the folding means in timed relation.

6. In an envelope machine, in combination, means for feeding envelope blanks continuously in spaced relation, flap lifters operating to lift the side flaps of the moving blanks,

and reciprocating side flap folders arranged to engage the lifted flaps and fold them inward while the blanks continue in motion.

7. In an envelope machine, in combination,
5 means for feeding envelope blanks continuously, means for folding the blanks while in motion, and flap lifting means reciprocating transversely of the plane traversed by the traveling blanks and timed to lift each blank
10 as it approaches the folding means to make sure that the blank flaps will be presented in a predetermined location relative to the folding means.

In testimony whereof I have affixed my
15 signature to this specification.
